FIG. 1

FIG. 2

FIG. 3

INVENTOR.
Rita FIRTH

UNITED STATES PATENT OFFICE

RITA FIRTH, OF CLEVELAND, OHIO

DESIGN FOR A TOY DOG

Application filed October 31, 1929. Serial No. 33,242. Term of patent 7 years.

To all whom it may concern:

Be it known that I, RITA FIRTH, a citizen of the United States, residing at 1532 Ansel Road, in the city of Cleveland, county of Cuyahoga, and State of Ohio, have invented a new, original, and ornamental Design for a Toy Dog, of which the following is a specification, reference being had to the accompanying drawing, forming a part thereof.

Figure 1 shows a front elevation of a toy dog, showing my new design.

Figure 2 is a side elevation of the toy dog, shown in Figure 1.

Figure 3 shows an enlarged view of a portion of the material consisting of circular rows of loose yarn loops with which the toy dog as shown in Figures 1 and 2, excepting the nose, is covered, giving my design a wooly appearance.

I claim:

The ornamental design for a toy dog as shown and described.

RITA FIRTH.
